Term of patent 7 years

(Cl. D61—1)

Fig. 1

Fig. 3

Fig. 2

Fig.4

Fig.5

Fig.6

Fig. 1 is a front perspective view of reflex type box camera embodying our new design.

Fig. 2 is a side elevational view thereof.

Fig. 3 is a top plan view.

Fig. 4 is a rear elevational view.

Fig. 5 is an elevational showing the side opposite that seen in Fig. 2.

Fig. 6 is a bottom plan view of the same.

The dominant features of our new design are shown in solid lines in the drawings.

We claim:

The ornamental design for a reflex type box camera, as shown and described.
